**POWER OPERATED HINGE-SEAT CUTTING
HAND TOOL**Arthur M. Sundby, 1915 14th Ave. S.,
Minneapolis 4, Minn.

Filed Dec. 22, 1958, Ser. No. 782,076

4 Claims. (Cl. 144—27)

This invention relates broadly to powered hand tools; more particularly to a novel type of portable electric circular saw; and specifically to an electric saw which will simultaneously cut the opposed seats for a hinge of the double leaf type, said hinge having semi-circular leafs especially for use with this tool in the door and in the door jamb.

It will be understood that for the purpose of this application the present invention will be continuously referred to, in the manner for which it is intended, to make simultaneous seat cuts for the hinge while the door is properly positioned in its frame. However, the tool obviously can be used and adjusted to make single cuts for seating a hinge as may be required. It will obviously be understood that by supplemental means the door will be rigidly wedged into position in the frame and held so positioned during the cutting operation. It will also be noted that with the tool positioned on the door preparatory to making the hinge cut, the thickness of the material of certain parts of the tool acts as a clearance gauge between the door and the jamb.

The special hinge for use with this tool is the subject matter of an application for U.S. patent filed of even date herewith.

Thus it will be seen that the principal object of this tool is to provide a unitary electric hand tool constructed and designed to simultaneously make semi-circular hinge cuts in the door and its frame, for a special hinge having semicircular hinge plates.

Another object of this invention is to provide a unitary electric hand tool for simultaneously making a semi-circular hinge plate cut wherein the tool when positioned for making said cuts acts as a spacer to provide clearance between the door and its frame when the same are in assembled relation.

A still further object of this invention is to provide a unitary electric hand tool of the class described that is convenient in size to use, transport, and store and which is light enough in weight to be lifted to its work without effort.

These and other objects of the invention will become apparent from the following specification and claims when taken in conjunction with the appended drawings in which, like characters indicate like parts throughout the several views.

To the above end, generally stated, the invention consists of the novel devices and combination of devices hereinafter described and defined in the claims.

Referring to the drawings:

Fig. 1 is a top plan view of the tool positioned on a door preparatory to making its simultaneous hinge cuts.

Fig. 2 is a right hand side elevational view of the same, showing the working position of the tool by means of broken lines.

Fig. 3 is a rear elevational view thereof.

Fig. 4 is a perspective view showing the tool position for making its simultaneous cuts.

The reference character X will hereinafter be directed

2

to the tool as an entirety, and of the non-component portions of the drawing, it is important to note the door 4, and the door jamb 5 and frame 5', taken as an entirety for the purpose of this application.

5 The numeral 6 indicates a rectangular base plate formed of sheet metal of sufficient gauge to give the same the desired stiffness for mounting component parts of the tool as will presently appear.

This base plate 6 is provided at its right hand longitudinal edge portion as viewed on Figure 1 with a pair of downturned flanges 7 and 8, said flanges being spaced apart to afford a clearance passageway for the cutting mechanism of the tool as will presently be described.

A webbed supporting arm 9 is constructed at its forward end portion to be mounted for pivotal movements in a vertical plane on a hinge plate 10 that is rigidly secured adjacent the forward edge of the base plate 6 by means of a plurality of nut-equipped bolts 11. A pintle 12 extends through the customary bores 13 in the hinge plate 10 and through aligned bores 14 in the forward end portion of the supporting arm 9 which is in the form of a fork. A stiff coiled spring 15 encircles the pintle 12 under strain with one end portion 16 thereof engaging the main body portion of the supporting arm 9, and the other end portion thereof engaging the base plate 10 to normally hold the supporting arm 9 and its mounted components in a raised position above the base plate 6. The outer or rear end portion of the supporting arm 9 is constructed to form a closed handle grip 17 and also affords a mount for an electric switch 18 of the trigger type for a purpose that will presently appear.

A boss 19 is formed integral with the supporting arm 9 and is internally threaded for engagement with a threaded hand screw 20 having a lock nut 21. A stud 22 is rigidly affixed to the base plate 6 in alignment with the lower end portion of the hand screw 20 and is provided to limit the downward movement of the supporting arm 9 and its mounted components.

An electric motor 23 has a reduction gear train rigidly mounted on the supporting arm 9, substantially at the longitudinal center thereof and with the axes of the armature shaft of the motor 23, the gear shaft 24 and the respective toothed gearing, not shown, in parallel arrangement with the longitudinal axis of the pintle 12. A circular saw 25, is secured to the gear shaft 24 and conventional electrical connection, not shown, between the motor 23, the switch 18 in the handle grip 17, and the source of power are provided to energize the motor 23 by closing the switch 18 that is normally held open by spring means, 50 by finger pressure thereon.

Operation

It will be, of course, understood that this tool is designed for a special hinge that is equally as efficient as any hinge commonly used today for hanging doors and the like. It is an obvious conclusion that a semi-circular hinge plate will serve its purpose as well as one of rectangular or square shape.

Obviously, there are numerous ways in which the door 4 may be held positioned in the frame 5' and spaced from the jamb 5 preparatory to making the cuts for the hinge plates 10. However, in the interest of clarity and simplicity for the purpose of this application, it will be assumed that the said door will be wedged in proper position with the tool also positioned on the door with the flanges 7 and 8 between the mounted edge of the door and the jamb for the purpose of providing clearance at that point. With the flanges 7 and 8 so positioned, the base plate will rest flush on the surface of the door 4 adjacent either the upper or lower edge portions thereof depending upon which cut is being made.

With the tool so positioned, it is only necessary to

energize the motor 23 by depressing the switch 18 to rotate the circular blade saw 25. It will be understood that the depth of the cut has been previously determined and set by adjustment of the hand screw 20. Thus with the saw blade rotating, the tool is advanced to its work by manual downward pressure on the tool by the operator until the lower end portion of the hand screw 20 engages the stud 22 in the base plate 6. Both the cuts for the respective hinge plates 10 are made simultaneously and in exact opposed alignment assuring a perfect fit and proper hanging of the door. Obviously, the same procedure would be followed in making the subsequent cuts for the center and lower hinges on a door and the jamb. The tool is merely removed from the position of the just noted cut and placed in proper position by inserting the flanges 7 and 8 between the mounted edge of the door 4 and the jamb 5 while the door remains in position.

While there are herein disclosed but a limited number of embodiments of the structure, process and product of the invention herein presented, it is possible to produce still other embodiments without departing from the inventive concept herein disclosed, and it is desired, therefore, that only such limitations be imposed on the appended claims as are stated herein or required by the prior art.

What I claim is:

1. A powered hand tool for simultaneously cutting hinge-seats for a door and a door jamb to receive opposed hinge plates, comprising in combination, a base plate, a supporting arm hingedly mounted on said base plate for pivotal movement relative to the base plate, an electric motor rigidly secured to said supporting arm and cutting means driven by said motor, said cutting means being advanced to its work by manually imparted pressure on the supporting arm and its mounted components.

2. A powered hand tool for simultaneously cutting hinge-seats for a door and a door jamb to receive opposed hinge plates, comprising in combination, a relatively thin and flat rectangular base plate, a pair of depending flanges integral with the right hand edge portion of said base plate, said flanges being at right angles to the surface of the base plate, a rearwardly projecting, elongated supporting arm hingedly mounted at one end portion of the base plate, thus permitting pivotal movement of the supporting arm, and means normally holding said supporting arm in a retracted position relative to the base plate, an electric motor energized by a switch integral with the

supporting arm, and cutting means in the form of a circular saw driven by the electric motor and advanced to its work as downward pressure is exerted on the supporting arm.

5 3. The structure defined in claim 2 further including means to limit the downward movement of the supporting arm and its mounted components, and means for locking said position.

4. A powered hand tool for simultaneously cutting hinge-seats for a door and a door jamb to receive opposed hinge plates, comprising in combination, a relatively thin and flat, rectangular base plate, a pair of depending flanges integral with the right hand edge portion of the base plate and at right angles thereto to afford a spacer and alignment means for the tool when the same is positioned on its work, said flanges being spaced apart longitudinally to afford a passageway therebetween, a rearwardly projecting elongated supporting arm hingedly mounted at one end portion to the base plate thus permitting pivotal upward swinging movement of the supporting arm, a hand grip formed in the rear end portion of the supporting arm and spring means normally holding the supporting arm in retracted position relative to the base plate, a hand screw having screw threaded engagement with the rear end portion of the supporting arm cooperating with a stop member in the base plate to limit the downward movement of the supporting arm, a geared electric motor secured to the underside of the supporting arm substantially at its longitudinal center, said motor being activated by a trigger switch adjacent the handle portion of the supporting arm, and a circular saw driven by the geared electric motor and advanced to its work by manual downward pressure on the handle portion of the supporting arm.
